UNITED STATES PATENT OFFICE.

EUGENE A. HIRSCHY, OF BROOKLYN, NEW YORK.

INSULATOR AND FASTENER FOR AERIALS.

Application filed February 10, 1925. Serial No. 8,256.

To all whom it may concern:

Be it known that I, EUGENE A. HIRSCHY, a citizen of the United States of America, and a resident of the city of New York, 5 borough of Brooklyn, in the county of Kings and State of New York, have invented a new and Improved Insulator and Fastener for Aerials, of which the following is a description.

10 My invention relates to fasteners for electrical wires and conductors and while capable of a wide range of use, it is more particularly intended for fastening and insulating indoor aerials to walls, moldings, 15 and the like.

The general object of my invention is to provide an insulator and fastener that will permit of an aerial being securely held in position at proper intervals on a wall, molding, 20 or the like, and embodying means for fastening the device in position as well as novel means to hold an aerial whether of the usual plain or twisted wire type or in the form of a flat ribbon, and to insure the 25 insulation of the aerial when secured as well as its position out of contact with any objects that would lessen the efficiency of the aerial.

Reference is to be had to the accompanying drawings forming a part of this specification, it being understood that the drawings are merely illustrative of one example of 30 the invention.

Figure 1 is a perspective view showing 35 my improved device applied to a molding strip and indicating by dotted lines two forms of aerials held by the device;

Figure 2 is a plan view of the device;

Figure 3 is a longitudinal section as indicated by the line 3—3, Figure 2;

Figure 4 is a perspective view of the holding element for the aerial.

In carrying out my invention in accordance with the illustrated example, a small 45 insulator body formed of a block 10 is provided, and embedded in the same at one end is the rear end of a fastening device here shown as in the form of a screw 11. The screw or equivalent fastening device 11 is 50 driven into a wall, strip, or the like along which the aerial is to be strung, there being shown a fragment of a molding strip A in Figure 1.

Embedded in the insulating block 10 at 55 the opposite end is the anchoring shank

member 13 of a hook-like or U-shaped fastener member 12 for the aerial or the like. The bill 14 of the element 12 lies against a surface of the block 10. The terminals 15 of the clamping portion 14 of 60 the element 12 is slightly deflected to facilitate the entrance of an aerial beneath said clamping member 14.

Either a round or twisted wire *a* indicated by dot-and-dash lines in Figure 1 may be 65 secured or a flat or ribbon-like aerial *b*. Aerial *a* is held against the end of block 10 by the bend 16 of the element 12 and advantageously the adjacent end of the block 10 is formed with a depression 17 to partially 70 receive aerial *a*. Said aerial *a* is passed beneath the member 14 to the bend 16, said bend and the depression 17 accommodating the aerial in a manner that it will be engaged and properly held by the bend 16. The ribbon aerial indicated at *b* is simply passed 75 edgewise beneath the clamping member 14 and is held thereby flat against the opposed face of the block 10. It will be seen that the block 10 fully insulates the aerial holding element 12 from the fastener 11 and that said element 12 is sustained remote from the surface of the strip, wall, or other part to which the device is attached. Thus, the aerial of whatever type it may be is maintained 80 out of possible contact with objects that might affect its efficiency.

I would state in conclusion that while the illustrated example constitutes a practical embodiment of my invention, I do not limit myself strictly to the exact details herein illustrated, since, manifestly, the same can be considerably varied without departure 85 from the spirit of the invention as defined in the appended claims.

Having thus described my invention, I 90 claim:

1. A device of the class described, having a body of insulating material, means on said body at one end to secure said body in position, and a retaining element for clamping a wire, said element being hook-shaped and presenting an anchoring member embedded in the insulating material of the body at the opposite end and insulated from the retaining element, the material of said element being return bent to present substantially a U-shape and lying at its free end adjacent a face of the body, that portion of said element which lies adjacent the face 100

103

110

110

of the body and the interior of said element at the bend thereof being both adapted to retain a wire.

2. A fastener for a wire, comprising a body having means at one end to secure it in position, a wire retaining element on the body at the opposite end and insulated from said means, said element being returned to present a bend and a terminal portion lying adjacent a face of the body, said terminal portion constituting a clamping member for a wire, and said bend adapted also to retain a wire, that end of the body adjacent the bend of said element having a depression.

10 3. A fastener for a wire, comprising a body having means at one end to secure it

in position, a wire retaining element on the body at the opposite end and insulated from said means, said element being returned to

present a bend and a terminal portion lying adjacent a face of the body, said terminal portion constituting a clamping member for a wire, and said bend adapted also to retain a wire, that end of the body adjacent the bend of said element having a depression.

4. A fastener for electric wires, said fastener comprising a body having means to secure it in position, and a hook-like element adapted to hold a wire, said element being returned to present a portion lying adjacent a face of the body, the bend of said hook-like element at the interior being spaced from the adjacent end of the body to accommodate a wire between said adjacent end of the body and said bend at the interior.

EUGENE A. HIRSCHY.
